UNITED STATES PATENT OFFICE.

ASHER PRITZKER, OF TORONTO, ONTARIO, CANADA.

ELECTRIC RADIATOR.

1,310,838.

Specification of Letters Patent. Patented July 22, 1919.

Application filed September 9, 1918. Serial No. 253,124.

To all whom it may concern:

Be it known that I, ASHER PRITZKER, manufacturer, of the city of Toronto, county of York, Province of Ontario, Dominion of Canada, a subject of the King of Great Britain, have invented certain new and useful Improvements in Electric Radiators, of which the following is a specification.

My invention relates to improvements in electric heaters or radiators, in which the heat rays generated by a resistance element are reflected by a polished metal reflector, of any desired shape.

One of the objects of the invention is to removably mount the electric heating-element base in the reflector, or equivalent member, without the use of brackets or other supports now essentially employed in various types of this class of electrical device, thereby providing a device of this class which will stand comparatively rough usage without any of the parts being broken or displaced. Another object of my invention is to make the terminal connections with the resistance-element at the back of the radiator, and preferably within the heating-element base, thereby providing a very compact and neat-appearing device, and one whereby I am enabled to couple the radiator to any suitable support. A still further object of the invention is to provide a heating-element base of a preferred shape, preferably of conical or bee-hive form, mounted as hereinafter particularly set forth, so that the heat-rays radiating from different portions of the base will strike the reflector at different angles and thus be facilitated in their escape from the reflector. By reason of the preferred or equivalent shape of the base, none of the heat rays are projected between the bottom of the base itself and the radiator, as in some makes of similar electrical devices.

Broadly considered, the device comprises a reflector through which a hole is formed; an electric heating element base made of any suitable insulating material such as porcelain, and provided with a coupling-flange which extends through the hole formed in said reflector and more or less snugly fitting the same, and projects therebeyond so that a closure-member for the rear end of said base may be coupled thereto in such a manner as to be readily removed therefrom. A resistance-element is wound around the outer surface of said base, and the terminals of

said element are passed into the interior of said base, which is preferably cored out, and suitable binding-posts are provided whereby electrical connection is had with the terminals of said resistance-element.

Figure 1 is a front elevation of one form of polished metal reflector in which is mounted my electric heating-element base, and Fig. 2 is a horizontal longitudinal section on the line 2—2, Fig. 1.

In the drawings, like characters of reference refer to the same parts.

A is the electric-heating element base made of any suitable insulating material, such as porcelain, and integrally formed therewith is a coupling-flange B. The outside diameter of the flange B is preferably sufficiently less than the outside diameter of the base A at its widest part, thus forming a shoulder C. D is the reflector, and it will be observed that the hole E is punched therethrough to permit the flange B to pass through the reflector. The shoulder C rests in contact with the reflector. The outer surface of the base A is provided with a spiral groove to receive the resistance-element F which is shown in the drawings in the form of a coil. In order to reduce expense, and also to reduce the weight of the base A, and further to facilitate the making of electrical connections with the terminals 2 of the resistance-element F, the base A is completely cored out. 3 are suitable binding-posts carried by the flange B, with which the terminals 2 of the resistance-element F have connection in the usual manner.

5 is a flanged cap designed to close the open end of the base A. This cap is provided with an apertured insulating bushing 6 held therein through which the wires 4 pass.

Any suitable means is employed to detachably couple the cap 5 to the flange B: a suitable means for this purpose comprises a plurality of U-shaped brackets 7, which are coupled by the nuts and bolts designated by the common numeral of reference 8, or equivalent elements, to the flange B. By means of screws 9, the cap 5, through the medium of its flange 10, is coupled to the brackets 7. By removing the screws 9, the cap 5 may be readily removed and permit the necessary electrical connections to be made without the necessity of having to remove the base A from its support or reflector D.

According to my invention, the base A is supported by its flange B in the reflector D, and, therefore, I overcome all disadvantages arising when the supporting means for 5 a heating-element base forms part of the circuit.

The construction disclosed is very simple, and while it is relatively cheap, still it is efficient and durable.

10 Since the base A is supported by its flange C in the reflector D or its equivalent, particularly when I use a parabolic-shaped reflector, I find that my manner of mounting the base A gives me greater heating efficiency and, at the same time, provides the reflecting surface of the reflector D with a uniform appearance thus greatly adding to the attractiveness of this device.

15 The heating-element base A is preferably conical or bee-hive in shape, though not essentially so.

20 Since the resistance-element F is not positioned between the base A and the reflector D, on the line of the shoulder C, it will be understood that each heat ray projected from the resistance-element carried by the base A will strike the reflector D, and readily escape therefrom. The increase in efficiency in my radiator is due to the fact that 25 the heat rays emitted by the resistance-element, are not "choked" within the radiator, but are permitted ready and rapid escape therefrom.

25 In Fig. 1 the resistance-element F is merely shown conventionally in dotted lines.

30 It will be observed that the base A provides a very convenient and positive means for concentrating about the axis of the reflector, the maximum length of resistance unit without undue "overhang" of this base beyond the face of the reflector, thereby permitting the flange B to support the base and the resistance element in the reflector 45 without employing clamping means for that purpose.

35 In my preferred shape of base A, the weight of the overhang decreases as the outer end thereof is approached, and this 50 construction allows for the proper balancing of the base in respect of the reflector.

40 While I have described what I consider to be the best embodiment of my invention, I desire it to be understood that the principle 55 may be embodied in different forms, without going outside the scope of the appended claims.

Claims.

1. An electric radiator comprising the 60 combination of a reflector provided with a hole therethrough; a heating-element base made of suitable insulating material and integrally provided with a flange extending longitudinally thereof, the outside diameter 65 of which is less than the diameter of the

said base at its widest part, thus forming an annular shoulder which abuts against the front side of said reflector when said flange is passed through said hole; a resistance element supported by said base; an apertured 70 housing-means inclosing the exposed end of said flange and comprising means whereby the said base is removably firmly held in the reflector in coöperation with said shoulder, and means whereby electrical connection is 75 made with the said resistance-element.

2. An electric radiator comprising the combination of a reflector provided with a hole therethrough; a conical-shaped cored heating-element base made of suitable insulating material and integrally provided with a flange extending longitudinally thereof, the outside diameter of which is less than the diameter of the said base at its widest part, thus forming an annular shoulder 80 which abuts against the front side of said reflector when said flange is passed through said hole, with which it has an easy fit; a resistance element supported by said base; an apertured housing-means inclosing the 85 exposed end of said flange and comprising means whereby the said base is removably firmly held in the reflector in coöperation with said shoulder, and means whereby electrical connection is made with said resistance-element. 90

3. An electric radiator comprising the combination of a reflector provided with a hole therethrough; a conical-shaped cored heating-element base made of suitable insulating material and integrally provided with a flange extending longitudinally thereof, the outside diameter of which is less than the diameter of the said base at its 100 widest part, thus forming an annular shoulder which abuts against the front side of said reflector when said flange is passed through said hole, with which it has an easy fit; a resistance element mounted in a spiral groove around the outer surface of that portion of the base which projects beyond the front side of the reflector, an apertured housing-means inclosing the exposed end of 105 said flange and comprising means whereby the said base is removably firmly held in the reflector in coöperation with said shoulder, and means whereby electrical connection is 110 made with said resistance-element. 110

4. An electric radiator comprising the combination of a reflector provided with a hole therethrough; a heating-element base made of suitable insulating material and integrally provided with a flange extending longitudinally thereof, the outside diameter of which is less than the diameter of the said 120 base at its widest part, thus forming an annular shoulder which abuts against the front side of said reflector when said flange is passed through said hole; a resistance-element supported by said base; means detach- 125

130

- ably attached to the exposed end of said flange and coöperating therewith and with said shoulder whereby said base is removably firmly held against longitudinal displacement in the reflector, and means whereby electric connection is made with the said resistance-element.
5. In an electric radiator, the combination with a reflector provided with a hole there-through, of a heating element base made of suitable insulating material designed to extend through said hole and project beyond each side of said reflector, and integrally provided with a projecting flange which rests against said reflector, and an apertured 15 detachable housing means attached to the end of said base which projects beyond the rear side of said reflector and adapted to co-operate with said projecting end and said flange whereby said base is held against 20 longitudinal displacement in the said reflector.
